UNITED STATES PATENT OFFICE.

NATHAN H. SUREN, OF NEEDHAM, MASSACHUSETTS, ASSIGNOR TO GAMEWELL FIRE ALARM TELEGRAPH COMPANY, OF NEW YORK, N. Y., A CORPORATION OF NEW YORK.

RELAY.

1,145,942.

Specification of Letters Patent. Patented July 13, 1915.

Application filed May 8, 1914, Serial No. 837,323. Renewed February 17, 1915. Serial No. 8,889.

To all whom it may concern:

Be it known that I, NATHAN H. SUREN, a citizen of the United States, residing at Needham, in the county of Norfolk and 5 State of Massachusetts, have invented an Improvement in Relays, of which the following is a specification.

This invention relates to relays adapted for use in signaling-systems and particularly fire-alarm telegraph systems.

The object of the invention is to provide a relay especially adapted to control the circuit of an electrically operated whistle, horn, signal-recorder, or other signal receiving-device for fire alarms and other signals, whereby the blasts of the whistle and horn and the dashes of the signal-recorder will have a predetermined and uniform 10 length regardless of the duration of the 20 length of the breaks produced by the signal-transmitter or other cause.

In the generally accepted standard of fire-alarm systems, a closed circuit is employed, and the circuit-controlling wheels 25 of the signal-transmitters, are of the skeleton type, whereby during the operation thereof, the circuit-closing periods are of the same duration and the open-circuit periods are of three different durations, the shortest being 30 between the successive closures of a number-group of a round of a signal, the next longest being between the successive number-groups of a round of a signal and the longest being between the successive rounds of a 35 signal, or, as it is sometimes stated, between the successive repetitions of the signal it being understood that usually the signal is repeated four times, each being commonly termed a round. The blasts of the 40 whistle and horn, and the dashes of the signal-recorder, are given during the afore-said open-circuit periods and it is very important that they shall be of approximately uniform duration regardless of the varying 45 duration of the open-circuit periods. The relay embodying the present invention is capable of so controlling the circuit or circuits, of the whistle, horn, signal-recorder, and other signal-receiving device or devices, 50 as to enable this uniform action to be accomplished.

In another application, No. 747,322, filed February 10, 1913, a relay is shown having the capability of controlling the circuit or circuits of the signal-receiving devices or 55 instruments, whereby such uniformity of action is obtained, but this invention involves an improvement upon said relay which possesses some advantages over the relay therein shown, among which may be 60 mentioned the production of a very wide gap upon the opening movement of the circuit-controlling members; and the employment of relay-magnets, such as are ordinarily used, whereas in said application the 65 relay-magnets are wound with many more convolutions than is ordinarily required in order to energize the actuator of the timed actuating-means.

The present invention consists in the combination of a relay-magnet, a circuit-controller for a local-circuit controlling the signal-receiving instruments, the movable member of which is responsive to retractive and attractive movements of the armature 75 of said magnet, respectively, to engage and subsequently disengage its fellow-member, and timed actuating or moving-means associated with said movable member arranged to permit movement of said movable member 80 in response to short open-circuit conditions of the controlling-circuit of the relay-magnet and to move said member to disengage its fellow-member at the end of a predetermined period of time in case the controlling 85 circuit remains open, said timed actuating or moving-means involving an electromagnet as an operating-element; also, in arranging said electro-magnet in the circuit which is controlled by the relay-magnet, whereby 90 it is responsive to the closures of said circuit produced by the relay-magnet; also in a timed actuating-mechanism which is arranged to be operated by means independent 95 of the relay-magnet and which is arranged to move the movable circuit-controlling member, thereby to open the local-circuit at the end of a predetermined period of time in case said circuit remains closed, which mechanism permits movements of said circuit-controlling member in response to the 100 retractive and attractive movements of the

armature of the relay-magnets; also in many combinations of elements and accessory features, as will be hereafter described.

Figure 1 is a front elevation of a relay embodying this invention, the front plate being removed to expose the operating parts. Fig. 2 is a plan view of the relay-magnet and controlling-magnet associated therewith and the controlling-member operated by said magnet. Fig. 3 is a side elevation of the timing-train and relay-magnet. Fig. 4 is a transverse vertical section of the device shown in Fig. 1, taken on the dotted line, 4—4, Figs. 5 and 6 are details to be referred to. Fig. 7 is a diagram of a circuit illustrating one arrangement of my newly devised relay therein.

Referring to Fig. 1, 10 represents a base-plate, of insulating material, upon which 20 is suitably supported the relay-magnet 12, having its armature 13, borne by one arm 14, of a bell-crank lever, loosely mounted on the pivot-shaft 15, the other arm 16 of said lever extending downward and supporting 25 the movable contact-member. As here shown, said movable contact-member consists of a plate 17, bearing a contact-element 18, arranged for engagement with a pair of stationary contact-members 19, and said member 17 is pivotally connected to the lower end of a lever 20, pivoted at 21 to the arm 16, and being thereby movable by and with said arm, and also independently thereof, and a spring 22 is connected with 35 the upper end of said pivoted lever 20 by which said lever is normally held against a stop-pin 23, when the armature of the relay is in attracted position, and a spring 26 is attached at one end to the lever 20, and 40 at the other end to the contact-member 17, by which said contact-member is normally held in elevated position and in engagement with the lower end-portion of the arm 16. Said contact member 17 has a projection 24, 45 which is arranged to extend beneath a projection 25 on said arm 16, thereby to engage said arm, but disengagement may be easily effected by a downward movement of said member 17 on its pivot. When the armature of the relay-magnet is retracted and the 50 arm 16 correspondingly moved these several parts borne by it are moved bodily in a direction toward the contact-member 19, to cause the contact-member 17 to engage therewith, and such engagement of the contact-members closes the local-circuit of the signal-receiving instruments. Such movement of the aforesaid parts is caused by 55 the spring 22, which, it will be observed, is attached at one end to the lever 20 and at the other end to a fixed point, as for instance to one of the side plates of the device. A stop-pin 23 is employed to limit the movement of the arm 16 upon retraction 60 of the armature of the relay-magnet. In

case the open-circuit period of the control-
ling-circuit of the relay-magnet is of short
duration, the armature of said magnet will
be attracted upon the cessation of said
period by the closure of the controlling-cir- 70
cuit, whereupon the aforesaid parts will be
returned to the position shown in Fig. 1.
Upon retraction and subsequent attraction
of the armature of the relay-magnet when
responding to interruptions of short dura- 75
tion, of the controlling-circuit, the relative
positions of the aforesaid parts will be
maintained, and the blasts of the whistle,
and horn, and the dashes of the signal-re-
corder, will be of uniform length, and will 80
correspond with the duration of the short
open-circuit periods.

Herein controlling-means are provided for
the movable contact-member 17, whereby
said member is moved independently of the 85
means heretofore described for moving it,
or in other words, independent of the relay-
magnet, so that in case the controlling-cir-
cuit of the relay-magnet remains open for a
longer period of time than the duration of 90
the short open-circuit periods, said contact-
member will be moved to open the circuit
of the signal-receiving instrument, thereby
to correspondingly limit the duration of the
blasts of the whistle and horn, and the 95
length of the dashes of the signal-recorder,
so that such blasts and dashes will be of
approximately the same duration and length
as the blasts and dashes produced upon the
occurrence of the short open-circuit periods, 100
thereby establishing the uniformity which is
required. In my application aforesaid, ac-
tuating-means are provided for accomplishing
this result, which are therein broadly
claimed, but herein the actuating or moving- 105
means comprises a controlling-magnet 30 ar-
ranged in the local-circuit which is con-
trolled by the relay contact-members, which
may be the circuit, or one of the circuits, of
the signal-receiving instruments, so that it 110
is responsive to the closures of said circuit.
The armature 31, of said controlling-magnet
30, is borne by one arm 32, of a bell-crank
lever, loosely mounted on the pivot-shaft 15,
the other arm 33 of said lever extending 115
downward and normally resting against an
adjustable stop, and said armature is nor-
mally in retracted position as the local-cir-
cuit is normally open. Said arm 33 is
loosely connected to a member 34, pivoted at 120
35, which is employed to disengage the mov-
able contact-member from the arm 16, and
said member 34 bears the ratchet-toothed
arm 36, which is pivotally connected to the
upper end of said member, and said ratchet- 125
toothed arm engages the ratchet-wheel 37,
secured to a shaft 38, bearing a toothed-wheel
39, which engages a toothed-pinion 40, se-
cured to a shaft 41, said shaft bearing the
escapement-wheel 42, which is engaged by a 130

pallet 43, secured to the pivot-shaft to which a bar 44, is secured, bearing weights 45. Said train of gearing, or any other suitable form of train which may be employed in lieu thereof, serves as and constitutes a timing-train by which movement of the member 34 is regulated. The ratchet-toothed arm 36, is held in continuous engagement with the ratchet-wheel 37, by a spring 46, and when said arm is moved in one direction, as for instance in a direction toward the right, Fig. 1, the ratchet-wheel will be rotated and the component parts of the train of gearing will be moved, which movement is governed by a pallet, yet said arm is permitted to be moved freely in the other direction, as for instance in a direction toward the left, Fig. 1, without moving said ratchet-wheel, thereby providing for a slow movement of the member 34, in one direction and a quick return. The member 34, has an extension or arm 50, with or without a roll thereon, for engagement with a projection 51 on the movable contact-member 17, and when said member 34 is moved in a direction toward the right said arm 50 will engage said projection 51 and will move said member 17, thereby to cause its engaging end-portion to disengage the engaging-projection 25 at the lower end-portion of the arm 16. The movable contact-member 17, when thus disengaged, is free to move independently of the arm 16, and as it is borne by the pivoted lever 20, it will be moved by said lever under the control of the spring 22, in a direction toward the left, and will move in a path beneath the pin 25, until its carrying-lever 20, engages the stop-pin 23 and subsequently, upon closure of the controlling-circuit the arm 16 will be returned and will reengage said member 17. It will be understood that the member 34, is moved upon attraction of the armature of the controlling-magnet, which is responsive to a closure of the local-circuit by the contact-elements 18 and 19, and in case said contact-elements remain in engagement until the member 34 of the timing-mechanism arrives in position to engage the contact-member 17, said member 17 will be engaged by said member 34 and caused to disengage the arm 16, and return to normal position, independently, thereby disengaging the contact-member 19 and opening the local-circuit which includes the signal-receiving instruments, and also the controlling-magnet 30, whereupon the blasts of the whistle and horn, and the dashes of the recorder will cease and the armature of the controlling-magnet will retract. Thus the duration of the blasts and the length of the dashes are determined in such case by the timing-mechanism and controlled by the local controlling-magnet. In this structure the contact-member 17 may have a long movement,

thereby to produce a wide gap when disengaged from the contact-member 19, and furthermore, as the relay-magnet only performs its regular functions of controlling the relay contacts, it may be wound accordingly, the power required to actuate the timing-mechanism being derived from the controlling-magnet 30, in the circuit, and the power required to return the movable contact-member 17, being derived from the spring 22. 75

In case an alternating current is employed as the energy for the circuit of the controlling-magnet 30, as is sometimes the case, I have herein provided means for holding the ratchet-toothed arm in continuous engagement with the ratchet-wheel, which consists of a bell-crank lever pivoted at 60, one arm, 61, of which, bears a detent for engagement with a series of teeth formed on the upper side of said arm 36, and the other arm 62, 85 of which, continuously engages the movable contact-member 17, and is held in engagement therewith by a spring 63. In case a direct current is employed, this detent carrying-member may be omitted. It will be understood that the timing-mechanism will be adjusted to consume about the same length of time in operating as the duration of the short open-circuit periods, so that upon the occurrence of the long open-circuit 95 periods, heretofore noted, the circuit of the signal-receiving instruments will be opened at approximately the time of cessation of the short open-circuit periods. 100

I claim:—

1. In a relay, the combination of a relay-magnet, armature and circuit-controller for a local-circuit, the movable member of which is responsive to retractive and attractive movements of the armature, respectively, to engage and subsequently disengage its fellow-member, timed moving-means associated with said movable-member for moving it to cause it to disengage its fellow-member at the end of a predetermined period of time in 110 case the armature remains retracted, said timed moving-means having an actuator arranged to be controlled by the local-circuit, substantially as described.

2. In a relay, the combination of a relay-magnet, armature and circuit-controller for a local-circuit, the movable member of which is responsive to retractive and attractive movements of the armature, respectively, to engage and subsequently disengage its fellow-member, timed moving-means associated with said movable-member for moving it to cause it to disengage its fellow-member at the end of a predetermined period of time in 115 case the armature remains retracted, said timed moving-means having an electro-magnet associated with it which serves as an actuator therefor, substantially as described. 120

3. In a relay, the combination of a relay-magnet, armature and circuit-controller for 130

5 a local-circuit, the movable member of which is responsive to retractive and attractive movements of the armature, respectively, to engage and subsequently disengage its fellow-member, timed moving-means associated with said movable-member for moving it to cause it to disengage its fellow-member at the end of a predetermined period of time in case the armature remains retracted, said 10 timed moving-means having an electro-magnet associated with it which serves as an actuator therefor, said electro-magnet being arranged in the local circuit, substantially as described.

15 4. In a relay, the combination of a relay-magnet, armature, armature-lever and a circuit-controller for a local-circuit, the movable-member of which is arranged for movement with said lever in both directions, thereby being responsive to retractive and attractive movements of the armature, and is also movable independently of said lever to disengage its fellow-member in case the armature remains retracted, and means 20 arranged to control its independent movement, substantially as described.

25 5. In a relay, the combination of a relay-magnet, armature, armature-lever and a circuit-controller for a local-circuit, the movable-member of which is arranged for movement with said lever in both directions, thereby being responsive to retractive and attractive movements of the armature, and is also movable independently of said lever to disengage its fellow-member in case the armature remains retracted, and means 30 arranged to control its independent movement, requiring a prolonged period of time for operation, substantially as described.

35 6. In a relay, the combination of a relay-magnet, armature, armature-lever and a circuit-controller for a local-circuit, the movable-member of which is arranged for movement with said lever in both directions, thereby being responsive to retractive and attractive movements of the armature, and is also movable independently of said lever to disengage its fellow-member in case the armature remains retracted, and timed-moving 40 means arranged to control its independent movement, substantially as described.

45 7. In a relay, the combination of a relay-magnet, armature, armature-lever and a circuit-controller for a local-circuit, the movable-member of which is arranged for movement with said lever in both directions, thereby being responsive to retractive and attractive movements of the armature, and is also movable independently of said lever to disengage its fellow-member in case the armature remains retracted, and means 50 arranged to control its independent movement, including an electro-magnet which serves as an actuator therefor, substantially as described.

55 8. In a relay, the combination of a relay-magnet, armature, armature-lever and a circuit-controller for a local-circuit, the movable-member of which is arranged for movement with said lever in both directions, thereby being responsive to retractive and attractive movements of the armature, and is also movable independently of said lever to disengage its fellow-member in case the armature remains retracted, and means 60 arranged to control its independent movement, including an electro-magnet controlled by the local-circuit which serves as an actuator therefor, substantially as described.

65 9. In a relay, the combination of a relay-magnet, armature, armature-lever and a circuit-controller for a local-circuit, the movable member of which is normally held in engagement with the armature-lever, whereby said member is movable with said armature-lever upon retractive and attractive movements of the armature to engage and disengage its fellow-member, and timing-means arranged to disengage said member from the armature-lever, permitting return 70 movement thereof independently of said lever to disengage its fellow-member in case the armature remains retracted, substantially as described.

75 10. In a relay, the combination of a relay-magnet, armature, armature-lever and a circuit-controller for a local-circuit, the movable member of which is normally held in engagement with the armature-lever, whereby said member is movable with said armature-lever upon retractive and attractive movements of the armature to engage and disengage its fellow-member, and timing-means arranged to disengage said member from the armature-lever, permitting return 80 movement thereof independently of said lever to disengage its fellow-member in case the armature remains retracted, and means arranged to control its independent movement, substantially as described.

85 11. In a relay, the combination of a relay-magnet, armature, armature-lever and a circuit-controller for a local-circuit, the movable-member of which is pivotally supported 90 on a lever which is pivotally connected to the armature-lever and is arranged for engagement with and disengagement from said armature-lever, whereby said member is movable with said armature-lever upon 95 retractive and attractive movements of the armature to engage and disengage its fellow-member and is also movable independently of said lever to disengage its fellow-member in case the armature remains retracted, and means arranged to permit reengagement of said member with the said lever upon attraction 100 of the armature, substantially as described.

105 12. In a relay, the combination of a relay-magnet, armature, armature-lever and a circuit-controller for a local-circuit, the movable-member of which is pivotally supported 110 on a lever which is pivotally connected to the armature-lever and is arranged for engagement with and disengagement from said armature-lever, whereby said member is movable with said armature-lever upon 115 retractive and attractive movements of the armature to engage and disengage its fellow-member and is also movable independently of said lever to disengage its fellow-member in case the armature remains retracted, and means arranged to permit reengagement of said member with the said lever upon attraction 120 of the armature, substantially as described.

125 13. In a relay, the combination of a relay-magnet, armature, armature-lever and a circuit-controller for a local-circuit, the movable-member of which is pivotally supported 130 on a lever which is pivotally connected to the armature-lever and is arranged for engagement with and disengagement from said armature-lever, whereby said member is movable with said armature-lever upon retractive and attractive movements of the armature to engage and disengage its fellow-member and is also movable independently of said lever to disengage its fellow-member in case the armature remains retracted, and means arranged to permit reengagement of said member with the said lever upon attraction of the armature, substantially as described.

magnet, armature, armature-lever and a circuit-controller for a local-circuit, the movable-member of which is pivotally supported on a lever which is pivotally connected 5 to the armature-lever and is arranged for engagement with and disengagement from said armature-lever, whereby said member is movable with said armature-lever upon retractive and attractive movements of the 10 armature to engage and disengage its fellow-member and is also movable independently of said lever to disengage its fellow-member in case the armature remains retracted, and timed moving-means arranged 15 to disengage said member from the armature-lever, permitting independent movement thereof, substantially as described.

13. In a relay, the combination of a relay-magnet, armature, armature-lever and a circuit-controller for a local-circuit, the movable-member of which is pivotally supported on a lever which is pivotally connected to the armature-lever and is arranged for engagement with and disengagement from 20 said armature-lever, whereby said member is movable with said armature-lever upon retractive and attractive movements of the armature to engage and disengage its fellow-member and is also movable independently 25 of said lever to disengage its fellow-member in case the armature remains retracted, and means arranged to disengage it from said armature-lever, permitting it to move independently thereof, said means 30 involving an electro-magnet which serves as an actuator therefor, substantially as described.

14. In a relay, the combination of a relay-magnet, armature, armature-lever and a circuit-controller for a local-circuit, the movable member of which is pivotally supported on a lever which is pivotally connected to the armature-lever and is arranged for engagement with and disengagement from 40 said armature-lever, whereby said member is movable with said armature-lever upon retractive and attractive movements of the armature to engage and disengage its fellow-member and is also movable independently 45 of said lever to disengage its fellow-member in case the armature remains retracted, and means arranged to disengage it from said armature-lever, permitting it to move independently thereof, substantially as described.

15. In a relay, the combination of a relay-magnet, armature, armature-lever and a circuit-controller for a local-circuit, the movable-member of which is pivotally supported on a lever which is pivotally connected to the armature-lever and is arranged for engagement with and disengagement from 50 said armature-lever, whereby said member is movable with said armature-lever upon retractive and attractive movements of the armature to engage and disengage its fellow-member and is also movable independently 55 of said lever to disengage its fellow-member in case the armature remains retracted, and means arranged to disengage it from said armature-lever, permitting it to move independently thereof, substantially as described.

16. In a relay, the combination of a relay-magnet, armature, armature-lever and a circuit-controller for a local circuit, the movable-member of which is pivotally supported on a lever which is pivotally connected to 70 the armature-lever and is arranged for engagement with and disengagement from said armature-lever, whereby said member is movable with said armature-lever upon retractive and attractive movements of the 75 armature to engage and disengage its fellow-member and is also movable independently of said lever to disengage its fellow-member in case the armature remains retracted, means arranged to disengage it 80 from said armature-lever, permitting it to move independently thereof, and means for reengaging said member with the armature-lever when the latter returns to normal position, substantially as described. 75

16. In a relay, the combination of a relay-magnet, armature, armature-lever and a circuit-controller for a local circuit, the movable-member of which is pivotally supported on a lever which is pivotally connected to 85 the armature-lever and is arranged for engagement with and disengagement from said armature-lever, whereby said member is movable with said armature-lever upon retractive and attractive movements of the 90 armature to engage and disengage its fellow-member and is also movable independently of said lever to disengage its fellow-member in case the armature remains retracted, means arranged to disengage it 95 from said armature-lever, permitting it to move independently thereof, means controlled by the relay-magnet for resetting said means, and means for reengaging said member with the armature-lever when the latter returns to normal position, substantially as described.

17. In a relay, the combination of a relay-magnet, armature, armature-lever and a circuit-controller for a local-circuit, the movable-member of which is pivotally supported on one arm of a spring-controlled bell-crank lever, pivotally connected to the armature-lever, said member having an engaging-portion arranged for engagement with an engaging-portion on the armature-lever, whereby said member is movable with said armature-lever upon retractive and attractive movements of the armature, to engage and disengage its fellow-member, and is also 100 movable independently of said lever to disengage its fellow-member in case the armature remains retracted, a pivoted time-controlled member arranged for movement into engagement with said contact-member to 105 disengage it from the armature-lever, permitting independent movement thereof, an electro-magnet controlling the movement of said pivoted member in one direction, and means to move said member in the other 110 direction, substantially as described. 115

18. In a relay, the combination of a relay-magnet, armature and circuit-controller for a local-circuit, the movable-member of which is responsive to retractive and attractive movement of the armature, respectively, to engage and subsequently disengage its fellow-member, timed moving-means associated with said movable-member for moving it to cause it to disengage its fellow- 125 130

member at the end of a predetermined period of time in case the armature remains in retracted position, and means controlled by the relay-magnet and arranged for engagement with said timed moving-means for preventing return movement thereof while the armature of the relay-magnet remains retracted, substantially as described.
